UNITED STATES PATENT OFFICE.

ALBERT K. LOVELL, OF NEW HAVEN, CONNECTICUT.

BOTTLE-STOPPER.

1,069,153.

Specification of Letters Patent.

Patented Aug. 5, 1913.

Application filed September 19, 1912. Serial No. 721,327.

To all whom it may concern:

Be it known that I, ALBERT K. LOVELL, a citizen of the United States of America, and resident of New Haven, in the county 5 of New Haven and State of Connecticut, have invented certain new and useful Improvements in Bottle-Stoppers, of which the following is a specification.

My invention relates to a bottle stopper 10 and has for its object to provide bottle closure mechanism which shall within itself contain all the elements necessary to enable it to be applied to the ordinary form of bottle or jar, without special construction of 15 the bottle, or attachment to it of a part of the stopper mechanism separate from the remainder, but which may readily be applied or removed bodily without the aid of mechanical contrivances and positively 20 held and secured by a resisting abutment comprising the ordinary flange, rim or bead commonly found on bottles and jars.

The specification and drawings comprise a substitute application in renewal of an 25 application filed June 5, 1911, Serial Number 633,338 and inadvertently abandoned August 5, 1912.

The invention consists in the novel closure mechanism and arrangement, construction 30 and combination of parts as more fully hereinafter described and claimed.

In the accompanying drawings forming a part of this specification, Figure 1 is an elevation of a bottle fitted with my improved closure. Fig. 2 is a central, vertical cross section through Fig. 1. Fig. 3 is a similar section through the external screw cap, but showing the remaining parts in elevation and part section, and with the 35 mechanisms unfastened, or in the operation of being applied to or removed from a bottle. Fig. 4 is an elevation similar to Fig. 1 of a modification of the device embodying the principle of cams instead of a screw for 40 forcing the parts to place. Fig. 5 is a similar elevation with the parts in the position for being applied to or removed from the bottle. Fig. 6 is a central vertical, cross section of Fig. 5, and Fig. 7 is a horizontal 45 cross section through Fig. 4 on the line 7, 7.

Referring to the drawings, 1 denotes the neck of an ordinary bottle, formed with the usual flange, rim or bead, 2, around its mouth or opening, 3. Said rim or bead 50 usually comprises an external enlargement of the neck, provided mainly to strengthen

and reinforce it for the insertion of a cork, and it is generally found of varying thickness and depth in bottles of every size and description. It necessarily forms an annular shoulder 4 on the neck, at its lower side, which shoulder has been employed as an abutment for various devices for securing the cork or closure of the bottle in place. It performs this function in the application 60 of my improved bottle stopper, which is described as follows:

Upon the neck of the bottle is received a tubular ferrule 5 having its upper part loosely fitting around the rim or bead 2 and formed with a screw thread 6. Below the thread the ferrule is of expanding diameter, or slightly conical increasing in size downwardly to a plane which corresponds to the shoulder of the bead when the ferrule is in 70 its proper position thereon. At said point the shell of the ferrule is bent inwardly to form a flange 7 substantially at a right angle to its body, which flange is adapted to hook under and engage or grapple with 75 the shoulder 4 of the bead as shown in Fig. 2. From the flange the shell is extended downward in an outwardly expanding collar 8, which is provided for the purpose of gripping and holding the ferrule, in the 80 adjustment and fastening of the closure in place on the neck of the bottle. The ferrule is formed with vertical slits 9 extending from its threaded portion to the bottom of the gripping collar, whereby such part is 85 virtually divided into a series of sections or flaps 10 for the purpose of rendering it expandable and adapting the flange 7 to be slipped over the bead 2 and then sprung 90 inwardly to engage it.

Fitted to screw upon the threaded part of the ferrule is a cylindrical screw threaded cap 11, provided with a disk *e* of cork or other suitable material at its upper end inside the shell thereof, which forms the bottle closure or stopper when the cap is screwed down upon the ferrule to engage the disk with the mouth of the bottle, as shown in Fig. 2. In the operation of applying the device to and sealing a bottle, the ferrule 100 is held in the proper position and from turning by means of the gripping collar 8, and the cap 11 is then screwed down upon it. In this movement the lower edge of the cap, after passing the threaded part of the ferrule will engage the smooth conical part 105 thereof below the thread, and by its cam-

ming action thereon will contract the flaps 10 and engage the flange 7 with the shoulder 4 of the neck of the bottle, whereby the action of the screw in forcing the disk down 5 upon the mouth of the bottle, is counterbalanced by the reactively upward strain and hold of the flange 7 upon the shoulder.

If the ferrule is of spring material and its normal shape is that in which the flange is 10 engaged with the shoulder of the bottle, then the action of the screw cap will be confined to holding the ferrule in such engagement with the shoulder, and in the act of removing the ferrule the sections will yield 15 and spring outwardly in passing over the shoulder. On the other hand if the normal shape of the ferrule is its state of expansion, then the cap will cam it to place on the neck of the bottle as well as hold it in such 20 position. If the ferrule be made of inelastic material, then in the act of being forced over the bead 2 the sections will be expanded, and the cap will subsequently cam them into grappling engagement with 25 the shoulder, and hold them there. All of these effects are contemplated in the use of the invention, dependent upon circumstances, but it is important that the screw threads of the ferrule should be wholly 30 separated from the grappling sections, and that the inward camming action upon the sections, by the cap, or the function of holding them in the engaged position should be performed by a smooth annular part of 35 the cap in engagement with smooth and unthreaded surfaces upon the sections instead of threaded surfaces, for which purpose the non-threaded part of the cap below the thread is provided.

40 In the constructive detail of the mechanism, it is preferable to make the ferrule as a split ring, or non continuous by cutting it longitudinally as indicated by the division 12 in Fig. 3. This enables the ferrule to be 45 closed in and entered into the cap without being screwed therein, in connection with which result, if the lower ends or terminals of both the thread of the ferrule and that of the cap be provided with stop shoulders 50 respectively designated by the characters 13 and 14, in Figs. 3 and 1, such shoulders will act as stop mechanism for preventing the cap from being unscrewed from the ferrule beyond the limits of the threads and re- 55 moved therefrom. By this arrangement the cap and ferrule may be always kept together, and both wholly removed from or applied to the bottle at one operation. The advantage of this, not only for the purpose 60 of cleaning the parts, but for convenience in applying the device to or removing it from the bottle, and also preventing mislaying or losing the part, or screwing them together with the threads crossed and thereby 65 injuring them, is of the utmost importance.

Though the ferrule cannot project above the mouth of the bottle, as the cap and its disk must be screwed down into contact with the neck, the mouth of the bottle may project above the ferrule, as shown in the 70 drawings, hence a particular size of stopper is not confined to a particular height of the rim or bead, but may be used with various heights of the bead, up to the point where the ferrule is flush with the mouth of the 75 bottle. This provides for adjustment of the device to conform to various sizes of bead in which the diameter remains unchanged.

Figs. 4 to 7 inclusive illustrate a modification of the invention in which the cap 21 is formed with a pair of opposite cam slots 22, taking the place of the screw thread, and the ferrule 23 has a pair of external pins or projections 24 engaging the slots. With 80 this construction the cap can be turned on the ferrule only about a half revolution, and the cam slots, to provide the required range of movement of the cap are made of abrupt or steep pitch in their central parts, and of 85 lesser pitch corresponding to that of the screw threads at the ends, where they engage the pins when the cap is screwed to place, as shown in Fig. 4, or in its extreme released position as indicated in Figs. 5 and 90 95 6. With the exception of the pins in place of screw threads the ferrule is of the same construction as that shown in Figs. 1, 2 and 3, the split ring construction enabling it to be placed within the cap by springing, and the pins thus engaged with the cam slots, and operating as stops to prevent the disconnection of the parts. It is evident that the slots could be cut through to the lower 100 edge of the cap as indicated by the dotted 105 lines in Fig. 4 to permit the removal of the cap from the ferrule when the same comprises a solid ring instead of being made expandable. The top edge of the cap should be provided with a milled band *m* to facilitate a hold upon it in removing it.

I claim as my invention:

1. A bottle closure comprising in combination a ferrule for clasping the neck of the bottle, provided with yielding grappling sections for engaging the shoulder of the neck flange, a closure cap mounted upon the ferrule and adapted to rotary movement thereon, means coacting between the cap and ferrule for drawing the cap axially of 115 the ferrule by its rotary action thereon to close the bottle by draft of the parts respectively against the mouth and neck flange, and stops for limiting the rotary motion of the cap on the ferrule after disengagement 120 of the grappling sections from the flange and holding the parts together when removed from the bottle.

2. The combination of a bottle closing cap, a ferrule fitted within the cap having 130

expansible holding sections and abutments for grappling the flange of the bottle, means for drawing the cap axially on the ferrule to compress the expansible sections upon the flange by reaction of the cap against the mouth of the bottle, and stops for limiting the motion of the cap in the reverse direction after disengagement of the grappling sections to hold the parts together when removed from the bottle.

3. The combination of a ferrule for clasping the neck of a bottle, provided with yielding grappling sections for engaging the shoulder of the neck flange, a closure cap revolvably mounted thereon, means coacting between the cap and ferrule for drawing the cap axially of the ferrule in its revolution thereon to close the bottle by draft of the parts respectively against the mouth and neck flange, and stops for limiting the rotary movement of the cap on the ferrule after disengagement of the grappling sections, from the flange, the ferrule being slit longitudinally throughout to admit of a closure for admission into the cap and passing of the stops to place.

4. A bottle closure comprising in combination a screw threaded ferrule for clasping the neck of a bottle provided with yielding grappling sections independent of the screw threads for engaging the shoulder of the

neck flange, a closure cap mounted thereon in screw threaded engagement with the ferrule, and provided with an annular part independent of the screw threads inclosing the grappling sections, and stops for limiting the movement of the cap on the ferrule after disengagement of the grappling sections from the flange to hold the parts together after removal from the bottle.

5. A bottle closure comprising in combination a ferrule for clasping the neck of a bottle provided with yielding grappling sections for engaging the shoulder of the neck flange and screw threaded above the grappling sections and a screw threaded closure cap mounted thereon having a disk fitted within it for closing the mouth of the bottle, the threads of the respective parts having terminal shoulders at the ends from which they would part from each other in disengaging the closure from the bottle, whereby the parts are held together when removed from the bottle.

Signed by me at New Haven, New Haven county, Connecticut, this 16th day of September, 1912.

ALBERT K. LOVELL.
